UNITED STATES PATENT OFFICE.

HERBERT T. BALLARD, OF NORRISTOWN, PENNSYLVANIA.

KNITTING MACHINE.

1,406,253.

Specification of Letters Patent. Patented Feb. 14, 1922.

Application filed January 15, 1920. Serial No. 351,701.

To all whom it may concern:

Be it known that I, HERBERT T. BALLARD, a subject of Great Britain, and a resident of the city of Norristown, county of Montgomery, State of Pennsylvania, have invented certain new and useful Improvements in Knitting Machines, of which the following is a specification.

The invention relates to a new fabric and 10 to the method and means for making the same. The invention is carried out on a rib knitting machine with multiple feeds. Changes are made in the stitch, say from plain to tuck, and from tuck to plain, and 15 these changes are made to advance in position around the fabric in one direction at one feed as the courses are knit at this feed, whereas at another feed, and consequently in different courses, the said changes are 20 made to lag and thus these changes take place spirally around the fabric, one change making the spiral advance in certain courses from wale to wale or groups of wales, while the other changes make the spiral lag in the 25 other courses and from wale to wale or groups of wales.

In the drawings,

Figure 1 is a front view, developed, of a number of feeds, including my improved 30 mechanism.

Fig. 2 is a side view of the mechanism shown at the right of Fig. 1.

Fig. 3 is a plan view in the nature of a diagram.

35 Fig. 4 is a conventional front view of the fabric produced by the organization shown in Figs. 1 to 3.

In these drawings 1 indicates the cylinder and 2 the dial of a rib knitting machine.

40 I have shown ordinary feeds at A, B and my special feeds at C, D.

At each of these feeds there is a thread guide 3 of ordinary form.

45 At feed C I mount a toothed wheel 4, the teeth of which mesh with the needle stems and the wheel is therefore rotated. Say the cylinder has 324 needles, I make the number of teeth in the wheel 4 such that it is not an exact divisor of the number of needles in the 50 cylinder. For instance, the number of teeth in the wheel is 65. This will not divide exactly into the whole number of needles in the cylinder, but on the contrary, there will be one needle less than the number required 55 to make the number of needles a multiple of

the number of teeth and thus for each revolution of the needle cylinder the revolution of the toothed wheel 4 will not synchronize therewith, in the sense that the revolutions will start on the same needle, but as in the 60 case just mentioned, where there is one needle less than the number necessary to make a complete revolution of the wheel, said wheel will lag in respect to the revolution of the needle cylinder. This wheel carries 65 cams c, c' in the form of segments standing up from the surface of the wheel. These cams alternate with intervening spaces c² so that the cam path is divided into four segments, two high portions, c, c', alternating 70 with two low portions c². These cams operate to change the stitch from plain to tuck and from tuck to plain and for this purpose a rod 5 rests on the cam path, it being guided vertically by a block or bracket 6. The 75 upper end of this rod is designed to operate a lever 7 pivotally mounted at 8 to the yarn guide bracket and having a link 9 extending through post 10 extending through a slot 11 in the dial cap and connected at its lower 80 end with the ordinary wing cam of the dial set, this being the cam which, in ordinary practice, projects the needle to take the new yarn.

When the rod 5 is lifted the wing cam 85 will be retired so that the needles will be projected only far enough to take the new yarn without causing the latches to shed the loops to a point back of them and hence tuck 90 stitches will be formed on these needles.

When the low part of the cam comes under the rod 5 the latter will fall and the wing cam will be drawn forward by the spring 12 and the needles will be advanced 95 to knit.

These changes as above stated will lag in respect to the revolutions of the cylinder, in the present instance, one needle at a time, though I do not limit myself in this particular.

At the feed D, however, the wheel 4' is provided with 46 teeth to engage the needles and as this number divides into 324 unevenly, there being two needles over in the remainder, it follows that the wheel 4' will 105 be advanced a distance of two needles at each revolution of the cylinder and hence the changes consequent upon the operation of this feed will be out of time with any given wale and may be said to advance in 110

respect thereto. This wheel 4' is provided with a single cam *d* extending over an angle occupied by 23 needles, it being one-half of the circuit of the wheel. This cam 5 operates upon a rod 5', which in turn operates a lever 7' having a connection similar to that described above, to the post 10' of a wing cam.

In the present drawing I show two plain 10 feeds at A, B which merely knit in the ordinary manner by casting off what loops there are on the needles and draw new loops. These feeds alternate with the special feeds above described. At this special feed D 15 when the rod 5' is lowered consequent upon the low part of the cam coming under it, ordinary knitting is done here.

The fabric produced by the above organization is shown diagrammatically in Fig. 4, 20 from which it will be seen that a diagonal or spiral striped formation is produced with the stripes running in opposite directions, and diamond shaped formations at the intersecting points, this result being due to 25 the lead and lag of the changes in the stitch and to the fact that the fabric at one feed is modified by the intermediate courses knit at the next feed.

By using different colored yarns at the 30 different feeds the changes in the fabric are made pronounced in appearance.

The difference in the character of the 35 stitches will also have the effect of distorting the courses and wales from straight lines and they will have the zig-zag structure shown.

By using three feeds the wheel with sixty-five teeth would be used, also the forty-six toothed wheel, and the feed B. The feed A 40 would be omitted.

This organization will give one diamond block of the fabric structure in which the order of knitting in the courses would be one tuck, one knit, and one tuck. The second block would be made up of one tuck, 45 one tuck and one knit and the third block would have one course knit, one knit, one knit.

With the four-feed organization the order 50 of the courses would be as follows: One block would have course one tuck, one knit, one tuck, and one knit.

The second block would be one tuck, one knit, one knit and one knit.

55 The third block would have all the courses of ordinary knit stitch.

The 65-tooth wheel makes approximately 55 five revolutions to each course. As it has two cams it will knit 10 spaced apart plain portions in each course because the preceding feed B is a plain feed.

Between these plain knit portions, the needles will take on a second loop and these will be cast at feed A so that at this feed 65 the tuck wales will be completed in the same

course. This would give a diagonal tuck stripe and a plain knit stripe alternating but running diagonally one way if only these two feeds were used.

At the next feed D at which the smaller 70 wheel is located, this wheel having 46 teeth will make approximately 7 revolutions to one round of knitting, and as it has one cam there will be seven changes in the wing cam to knit seven times and to tuck seven times 75 in one course.

The machine has 324 needles as above stated. The wheel at feed C has 65 teeth. It has two cams and as the number of needles is not a multiple of the number of 80 teeth, the wheel changes its position with respect to the needle cylinder at each revolution of the latter, so that it will not start its series of revolutions per revolution of the cylinder on the same needle but on the contrary, on the next needle.

This wheel may be said to lag in respect to the revolutions of the cylinder, there being one needle lacking in the cylinder, of a sufficiency to make its five revolutions even 90 with those of the cylinder. We will follow the action of one needle through 33 courses of knitting, i. e. through the changes that the wheel at C goes through before repeating, it being obvious that with two cams its 95 action repeats itself after 33 courses.

I do not limit myself to the combination of feeds and the employment of the two special feeds and controlling means, such as both of the toothed wheels 4, 4' in the same machine. The drawings and description are 125 illustrative of my invention and are not to be considered in a restricting or limiting sense, the scope of the invention in both its broader and particular aspects being defined by the appended claims. The fabric is the 130

subject of another application Serial No. 502,678, filed Sept 23, 1921.

I claim:

1. A rib knitting machine having at each of two feeds means for making tuck and plain fabric, and having a plain feed, controlling means at each of the two feeds first mentioned with means for operating them to make alternately in each course a series 10 of tuck stitches and a series of plain rib stitches to form bands so that one of said means will advance in its operation in successive courses in respect to the wales of stitches and the other will lag in its operation 15 in successive courses in respect to the wales of stitches whereby the changes in the stitches at one feed will advance in one direction around the fabric and the changes at the other feed will lag in the opposite direction 20 around the fabric, and diamond shapes will be formed where two spiral bands cross, substantially as described.
2. A rib knitting machine comprising two feeds with means at each feed for changing from plain to tuck and from tuck to plain 25 stitches on the dial needles, a plain feed, and controlling means at each of the two feeds first mentioned for timing the changes to produce bands advancing around the fabric 30 in successive courses in one direction at one feed and lagging in successive courses in the other direction at the other feed, the changes in the fabric structure thus occurring along spiral lines about the fabric, said bands crossing each other to form diamond blocks, substantially as described.
3. A rib knitting machine comprising two feeds with means at each feed for changing from plain to tuck stitches and from tuck to plain 35 stitches, and controlling means comprising a toothed wheel at each of said feeds driven from the machine, one advancing as

to the beginning of its revolutions in respect to the revolutions of the machine and the other lagging in its revolutions in respect to 45 the revolutions of the machine and connections to the wing cams operated by the said wheels, substantially as described.

4. A rib knitting machine comprising two feeds with means at each feed for changing 50 from plain to tuck stitches and from tuck to plain stitches, and controlling means comprising a toothed wheel at each of said feeds driven from the machine, one advancing as to the beginning of its revolution in respect 55 to the revolutions of the machine and the other lagging in its revolutions in respect to the revolutions of the machine and connections to the wing cams operated by the said wheels, said toothed wheels meshing with 60 the stems of the cylinder needles to be rotated therefrom, substantially as described.

5. In combination with a rib knitting machine, a yarn feed, means for changing the stitch from tuck to plain and from plain to 65 tuck, and means for controlling the time of said changes comprising a toothed wheel driven from the machine but non-synchronous in its revolutions in respect to the revolutions of the machine to make the changes 70 appear spirally around the fabric, said toothed wheel engaging the stems of the cylinder needles to receive rotation therefrom.

6. In combination with a rib knitting machine, a dial wing cam, a toothed wheel 75 driven from the machine, a cam on the wheel, a rod operated by the cam, a bell crank lever, a link operated thereby and reaching over the dial and a post extending up from the wing cam and to which the link 80 is connected.

In testimony whereof, I affix my signature.

HERBERT T. BALLARD.
